UNITED STATES PATENT OFFICE.

JOSEPH J. AIREY, OF PITTSBURG, PENNSYLVANIA.

HOT-BLAST STOVE.

SPECIFICATION forming part of Letters Patent No. 296,101, dated April 1, 1884.

Application filed September 18, 1883. (No model.)

To all whom it may concern:

Be it known that I, JOSEPH J. AIREY, of Pittsburgh, in the county of Allegheny and State of Pennsylvania, have invented certain new and useful Improvements in Hot-Blast Stoves; and I do hereby declare that the following is a full, clear, and exact description of the invention, which will enable others skilled in the art to which it appertains to make and use the same, reference being had to the accompanying drawings, which form a part of this specification, in which—

Figure 1 is a longitudinal vertical section of the stove on line *y y*. Fig. 2 is a transverse vertical section on line *x x*. Fig. 3 is a detail plan section of the door, &c.

This invention relates to the construction of hot-blast stoves, and has reference both to the form of the stove itself for maximum heating effect and to the appliances for regulating the heat and observing the same, as also to safety devices to prevent injury by explosion.

The invention consists in the combination and arrangement of parts, as hereinafter fully described and claimed.

A designates the primary combustion-chamber, arranged transversely of the stove structure at one end, as shown. This chamber communicates with the flue 1, which passes back to the rear end, then communicates with another horizontal flue, 2, which runs forward, and in turn communicates at its forward end with a similar flue, 3, passing backwardly again and at the rear communicating with flue 4. Thence an uptake, 30, enters a second tier of horizontal flues, 5, 6, 7, and 8, in reverse order, then by uptake 9 to a third tier of horizontal flues, 11, 12, 13, and 14, in similar order, thence by uptake 15 to a fourth tier of horizontal flues, 16, 17, 18, and 19, thence by uptake 20 to a fifth tier of horizontal flues, 21, 22, 23, and 24, whence the products of combustion pass off by flue 25 to the chimney or stack.

It will be observed that in the horizontal tiers of flues any one flue communicates with the preceding and following flues at opposite ends only, so that the gases and products of combustion travel the whole length of each flue. This gives an enormous heating-surface

to the stove, and is very simple and comparatively cheap.

The roof of the chamber A is arched and an inverted arch built above it, and all the heating-flues are likewise formed with a right and an inverted arch, as shown, the object being to enable the flues to resist the strains of the occasional explosion of the gas which takes place when the gas is first admitted for a heat. The precise number, vertically or horizontally, of the heating flues or tiers thereof is not particular. The number will be determined by the size of the flue-section or by the amount of air it is desired to heat. When the flues are heated to the requisite extent, the gas is shut off and the air-blast admitted in a reverse direction by the inlet B, whence it passes through all the flues in succession, becoming hotter as it goes until finally it emerges from flue 1 into chamber A, whence it passes out by outlet C to the hot-blast pipe, and thence to the furnace. The gas-pipes and air-pipes are of course provided always with suitable valves for controlling the admission of air and gas to the stove.

In the end wall, D, of the stove I form openings E opposite the ends of the various flues, as shown. Each of the openings E is fitted with a swinging door, f, hung from its upper edge to a suitable framing provided with extensions g. Across the extensions g, at a proper distance from the door, I pivot a lever, h, bearing at one end against the door f, and at the other end having a weight, i. The weights i are designed so as to hold the doors shut against the normal or regular pressure of the gas or blast, but to yield to any excessive pressure. The consequence is that when explosion takes place from any cause the doors f yield outwardly and prevent injury to the stove and flue structure. Similar doors are placed at the other end of the stove—one opposite the flue 11, and one in chamber A near the gas-inlet k—where, besides an explosion-valve, it serves also as a register to admit the proper amount of air to start combustion of the gas.

In each of the doors f, or in any desired number of them, I form the tubular extension m, preferably with a flaring mouth. Through

m, vertically, I set a tapered rotary plug, *n*, having in the line of the bore two ports, *p*, one of which is open, and the other closed by a suitable glass or mica partition, *r*, as shown 5 in detail section in Fig. 3. Each plug *n* has a suitable handle, *s*, for operating. In the position shown in Fig. 3, the tube *m* is open, and a pyrometer can be inserted to test the heat in the flue, while in a position at right angles to 10 that shown the tube *m* would be closed by the glass or mica *r*. In an intermediate position the plug acts as an air-valve to admit any desired quantity of air to complete or promote combustion of the gas passing through the flues. 15 By arranging the chamber A transversely much greater strength and resisting power is obtained than if it were located parallel with the heating-flues. 20 By arranging two or more flues in vertical order, as shown, great facility exists for repairs, as, if the arches require rebuilding, (the vertical walls never needing rebuilding,) the workman can begin above, and after tearing out, say, the arches between flues 24 and 16 25 he can stand up to the remaining work till all are removed, after which he builds the arches in in the reverse order.

I am aware that it is not new, broadly, to

construct a hot-blast stove having a number of communicating flues—one over the other—and 30 hence I do not claim such construction.

I claim as my invention—

1. In a hot-blast stove, the combination of a series of horizontal flues communicating each at its end with the flue next adjacent, the last 35 flue of the series communicating by a vertical flue with a second series of similar flues above, substantially as described.

2. In a hot-blast stove, the combination of a horizontal combustion-chamber with a series 40 of communicating flues arranged side by side and running in a direction at right angles to the direction of said combustion-chamber, substantially as described.

3. In a hot-blast stove, one or more wall- 45 openings communicating with the heating-flues, provided with swinging doors *f*, having tubes *m*, and plugs *n*, having openings *p* and partition *r*, substantially as described.

In testimony that I claim the foregoing as 50 my own I have hereto affixed my signature in presence of two witnesses.

JOSEPH J. AIREY.
